(57) **CLAIM**

The ornamental design for a computer terminal, as shown and described.

DESCRIPTION

FIG. 1 is a front perspective view of a computer terminal showing our new design;

FIG. 2 is a front view thereof;

FIG. 3 is a rear view thereof;

FIG. 4 is a right side view thereof;

FIG. 5 is a left side view thereof;

FIG. 6 is a top plan view thereof; and,

FIG. 7 is a bottom plan view thereof.

The broken lines in the drawings illustrate unclaimed portions of the computer terminal and form no part of the claimed design.
